UNITED STATES PATENT OFFICE.

GEORGE S. HILL, OF STRAFFORD, NEW HAMPSHIRE, ASSIGNEE, BY MESNE ASSIGNMENTS, TO UNITED SHOE MACHINERY CORPORATION, OF PATERSON, NEW JERSEY, A CORPORATION OF NEW JERSEY.

SEWING-MACHINE.

1,276,359.

Specification of Letters Patent. Patented Aug. 20, 1918.

Original application filed June 19, 1916, Serial No. 104,449. Divided and this application filed March 19, 1917. Serial No. 155,847.

To all whom it may concern:

Be it known that I, GEORGE S. HILL, a citizen of the United States, residing at Strafford, in the county of Strafford and State of New Hampshire, have invented certain new and useful Improvements in Sewing-Machines; and I do hereby declare the following to be a full, clear, and exact description of the invention, such as will enable others skilled in the art to which it appertains to make and use the same.

The invention relates to machines for sewing overseams, and more particularly to machines adapted for sewing buttonholes.

15 The present application is a division of application Serial No. 104,449, filed June 19, 1916.

The object of the invention is to provide novel and improved looper and loop spreader mechanism for coöperating with the upper needle or needles of the sewing mechanism. Heretofore it has been customary, in sewing machines of the class to which this part of the invention relates, to 20 pivot the loop spreaders on the oscillating support which carries the looper points, and to swing the spreader points laterally, either by stationary cams against which the tails of the spreaders are alternately carried by the oscillations of the looper carrier, or by similar cams which are moved to meet the spreaders, the spreaders in either case being held in normal position on the looper carrier by springs which yield as 25 the tails of the spreaders ride on to the spreader actuating cams. The use of springs and bunt cams with which the spreaders contact during the oscillation of the looper carrier is objectionable, and limits 30 the speed at which the mechanism may be operated. The objectionable springs and bunt or sliding cam connections are eliminated in the looper and loop spreader mechanism of the present invention by providing 35 a mechanism which acts independently of the reciprocation of the looper carrier, to give the transverse loop spreading movements. These movements are preferably effected 40 through positive connections from an eccentric or other actuator, so that the operation of the mechanism will be uniform and certain at high speeds, for which the usual 45 constructions are unsuited.

The various features of the invention will be readily understood from an inspection of 55 the accompanying drawings and the following detailed description of the machine shown therein.

In the drawings, Figure 1 is a sectional elevation showing so much of a buttonhole 60 sewing machine as is necessary to illustrate the application of the present invention thereto; Fig. 2 is a partial transverse sectional elevation on line 2, Fig. 1; Fig. 3 is a detail plan view of the turret which carries 65 the under sewing mechanism; Fig. 4 is a sectional elevation on line 4, Fig. 3; and Figs. 5 to 13 are diagrammatic views showing the mode of operation in forming over-seam stitches, Fig. 13 being a sectional view 70 on line 13, Fig. 12.

In the drawings, the invention is shown as embodied in a buttonhole making machine comprising in general a cutter which operates to cut the buttonhole slit after the 75 completion of the sewing, a reciprocating and laterally moving work clamp, and a sewing mechanism which is rotated during the sewing about the eye of the buttonhole, and which comprises a vertically reciprocating 80 and laterally vibrating or jogging upper needle, and coöperating looping and loop spreading devices arranged below the work.

In the machine shown the work clamps, indicated at 2, are mounted upon the work 85 supporting plates 4 which are pivoted on a longitudinally and laterally moving clamp carriage 6. The clamps are automatically closed at the beginning of the sewing, and are automatically opened after the completion of the buttonhole, by mechanism which forms no part of the present invention, and which need not be described. The button-hole slit is cut after the completion of the 90 sewing by a cutter 8 operated by a cam on the main cam shaft of the machine. The work is carried by the clamp over a throat plate 10 mounted on the turret 12 which carries the under looping and loop spreading mechanism.

100 In the embodiment of the invention shown, the sewing mechanism is adapted to form the well-known Humphrey stitch and comprises a vertically reciprocating and laterally jogging upper needle 14, and two 105 pairs of opposed looper and loop spreader

points arranged to reciprocate below the throat plate and constructed to alternately enter the loops thrown out by the needle. The two looper points 16 and 18 which co-
5 operate with the upper needle in forming the stitches are secured in the arms 20 of a looper carrier 22 which is provided with two bearings 24 mounted to turn on the inner ends of studs 26 which are secured in lugs
10 28 projecting from the upper edge of the turret (Figs. 2 and 3). The looper 16 is provided with a thread guide and thread eye for the under thread carried by this looper. The looper carrier is oscillated through a
15 link comprising a lower tubular part 30, to the upper end of which is adjustably secured an arm 32 pivotally connected at its upper end to the looper carrier. The lower end of the link is connected by a ball joint
20 with the forward end of a lever 34, the rear end of which is connected to the lower end of a rod 36. The upper end of the rod carries a fork 38 which embraces a three-cornered eccentric 40 on the sewing shaft. The
25 fork is supported and guided by a link 42. The loop spreaders which coöperate with the loopers comprise two spreader points 44 and 46 secured in the upper ends of two vertical arms of a spreader carrier lever 48
30 and arranged to overlie the loopers 16 and 18. The spreader carrier is mounted on a pivot 50 carried by the looper carrier and arranged at right angles to the axis of the looper carrier. The carrier lever is pro-
35 vided with a horizontal arm 52 arranged substantially in the axis of the looper carrier, and having its outer end connected by a ball and socket joint to the upper end of an arm 54, the lower end of which is adjust-
40 ably secured to the upper end of a tube 56 which extends down through the tube 30, and is connected at its lower end by a ball joint to the forward end of a lever 58, the tube and arm forming a link connecting the
45 lever 58 with the spreader carrier lever. The under looper thread passes up through the tube 56 to a tension device 57 on the turret, from which it leads through suitable thread guides to the looper 16. The spreader carrier lever is oscillated by an eccentric 60 on the needle shaft which engages the upper end of a rod 62, the lower end of which is connected to the rear end of the lever 58. In this construction the transverse loop
50 spreading movements are not effected by or dependent upon the reciprocatory movements of the carriers, but are effected independently of such reciprocatory movements, and by positive connections between the
55 transversely movable carrier and the actuating eccentric or other actuator. The looper and spreader mechanism is therefore well adapted for operation at maximum speed.

The mode of operation of the loopers and
60 spreaders in coöoperating with the upper

needle to form the overedge stitches is illus-
trated in Figs. 5 to 13. During the depth
stroke of the upper needle the looper car-
rier is rocked toward the left in Fig. 5 to
project the end of the looper 18 and the over-
lying spreader point 46 through an upper
needle loop thrown out by the needle as it
starts upward from its lowest position.
This loop is carried toward the left by the
looper 18 into the position indicated in Fig.
75 5, and as it is carried into this position the
spreader lever is rocked transversely of the
direction of travel of the looper to spread
the loop, as indicated in Fig. 6, so that dur-
ing the slit or edge stroke of the needle it 80
will pass down through the loop of upper
thread. After the needle has entered the
loop, the looper carrier is rocked toward the
right, the spreader lever being rocked to re-
turn the spreaders to initial position, as in-
dicated in Figs. 7 and 8. During the con-
tinued movement of the looper carrier to-
ward the right, the looper 16 and overlying
spreader point 44 pass through a loop
thrown out by the needle as it starts up-
ward, the position of the parts as the looper
is entering the needle loop being indicated
in Figs. 9 and 10. The continued movement
of the looper carrier toward the right car-
ries the under looper thread through the
loop of needle thread, and the spreader le-
ver is rocked to move the spreader trans-
versely of the looper and spread the looper
thread and present it in position for the
passage of the needle during the next depth
stroke, as indicated in Figs. 11 and 12.
After the needle has passed through the loop
of looper thread, the looper carrier is again
rocked toward the left, the spreader lever
being rocked to return the spreaders into
position above the loopers, so that the looper
100 18 and spreader 46 may again take a loop of
upper thread from the needle, spread it, and
present it in position for the passage of the
needle during its next slit stroke.

The mechanism for vibrating or jogging
the needle 14 comprises a vertically recipro-
cating and laterally vibrating carrier sleeve
64 within which the needle bar 66 recipro-
cates. The carrier sleeve is reciprocated ver-
tically through a bell crank lever 68, the
horizontal arm of which is connected by a
ball joint with the upper end of the sleeve,
and the vertical arm of which is connected
by a link 70 with an eccentric on the sewing
shaft. The lower end of the sleeve is moved
laterally by a link 72, one end of which is
connected to the sleeve, and the other end
of which is connected with a pivot 74 on a
rotary head 76. When the sleeve is moved
downward the link acts to swing the lower
end of the sleeve and the needle bar toward
the right, so that the needle bar will be po-
sitioned for the depth stitch. When the
sleeve is raised the link acts to swing the
110 120 125 130

sleeve toward the left, so that the needle bar will be positioned to form the slit or edge stitch. The needle bar is reciprocated by a crank 78 on the needle shaft which is connected to the needle bar by a link 80. Since the needle shaft makes two revolutions for each revolution of the sewing shaft, the needle carrier will be moved to the right during one reciprocation of the needle, and to the left during the succeeding reciprocation, so that the needle will be vibrated or jogged to alternately form the depth and edge or slit stitches.

The rotary head 76 in which the carrier sleeve and needle bar are carried, and the rotary turret 12 in which the looper mechanism is carried, are rotated in unison during the sewing about the eye of a buttonhole through shafts 82 and 84 geared to the head and turret, and operated by connected gear segment levers 86 and 88, one of which is provided with an arm carrying a roll engaged by a cam on the cam shaft of the machine.

25 The loop entering points of the looper and loop spreader mechanism are preferably provided with shanks which fit and are clamped within sockets at the upper end of the carrier arms, so that the points may be readily secured in place or removed. This enables adjustments or repairs to be readily made, and also enables different forms of points to be readily substituted in case a change in the character of the seam, as, for 30 instance, a change from a two-thread to a one-thread seam, is desired.

While the invention has been shown and described as embodied in a construction in which two opposed looper points are secured 40 in a reciprocating or oscillating support, and two coöperating spreader points are secured in a transversely movable carrier mounted on the oscillating support, it will be understood that certain features of the invention 45 are not limited in their application to mechanism embodying two pairs of looper and loop spreader points, but may be embodied with advantage in mechanism embodying a less number of spreader or looper points, 50 and it will also be understood that the specific manner of mounting and arranging the looper and loop spreader points shown and described is not essential, and that the points may be otherwise mounted, or may be otherwise 55 distributed or arranged on the support and carrier to secure the relative transverse movements between the spreader and looper points requisite for properly coöperating with the needle in forming the stitch for 60 which the sewing mechanism in which the invention is embodied is designed or intended. It will also be understood that the invention is not limited to the specific construction and arrangements of parts shown 65 and described, but may be embodied in other

constructions, and that the specific construction or arrangement of the parts may be varied or modified as found desirable or best suited to the machine or mechanism in which the invention is to be embodied.

Having explained the nature and object of the invention, and specifically described one form of mechanism in which it may be embodied, what is claimed is:—

1. A sewing machine, having, in combination, an upper needle mechanism above the work, and looper and loop spreader mechanism below the work comprising a reciprocating looper carrier, two loopers 75 thereon, coöperating loop spreaders mounted to move with the loopers during their reciprocation, and mechanism acting independently of the reciprocation of the looper carrier to relatively move a looper and coöperating spreader transversely each stroke 80 of the looper carrier.

2. A sewing machine, having, in combination, an upper needle mechanism above the work, and looper and loop spreader mechanism below the work comprising an oscillating carrier, a transversely movable carrier moving with the oscillating carrier, looper and loop spreader points on the carriers, an actuator, and positive connections 90 from the actuator to the transversely movable carrier for imparting transverse reciprocations thereto.

3. A sewing machine, having, in combination, an upper needle mechanism above the work, and looper and loop spreader mechanism below the work comprising an oscillating carrier, a transversely movable carrier mounted thereon, looper and loop spreader points on the carriers, an eccentric, and positive connections from the eccentric 100 to the transversely movable carrier for reciprocating said carrier transversely.

4. A sewing machine, having, in combination, an upper needle mechanism above the work, and looper and loop spreader mechanism below the work comprising reciprocating looper points, loop spreader points mounted to move with the looper points and connected to move transversely in unison, and mechanism for moving the spreader 105 points transversely toward and from the looper points.

5. A sewing machine, having, in combination, an upper needle mechanism above the work, and looper and loop spreader mechanism below the work comprising an oscillating looper carrier provided with looper points, a spreader carrier mounted on the looper carrier and provided with loop spreader points, an actuator, and positive 110 connections from the actuator to the spreader carrier through which transverse movements are transmitted to the spreader points.

6. A sewing machine, having, in combina- 115

- tion, an upper needle mechanism above the work, and looper and loop spreader mechanism below the work comprising an oscillating looper carrier provided with looper 5 points, a spreader carrier mounted on the looper carrier and provided with loop spreader points, an eccentric, and positive connections from the eccentric to the spreader carrier for transversely reciprocating the spreader carrier.
7. A sewing machine, having, in combination, an upper needle mechanism above the work, and looper and loop spreader mechanism below the work comprising an oscillating support, a carrier mounted on the support to oscillate about an axis substantially at right angles to the axis of the support and provided with loop engaging points, mechanism for oscillating the support, and 15 mechanism for oscillating the carrier on the support at twice the speed of the support.
8. A sewing machine, having, in combination, an upper needle mechanism above the work, and looper and loop spreader mechanism below the work comprising an oscillating carrier, a second carrier mounted thereon to rock about an axis substantially at 25 right angles to the axis of the oscillating carrier, mechanism for oscillating the first carrier and for rocking the second carrier at twice the frequency of the first mentioned carrier, and looper and loop spreader points on the respective carriers.
9. A sewing machine, having, in combination, an upper needle mechanism above the work, and looper and loop spreader mechanism below the work comprising a looper 35 carrier, a spreader carrier mounted to move with and transversely of the looper carrier, two loopers on the looper carrier, and two coöperating loop spreaders on the spreader carrier.
10. A sewing machine, having, in combination, an upper needle mechanism above the work, and looper and loop spreader mechanism below the work comprising two carriers mounted to reciprocate in unison and for relative movement transversely of 45 their line of reciprocation, and two pairs of looper and loop spreading points on the carriers.
11. A sewing machine, having, in combination, an upper needle mechanism above the work, and looper and loop spreader mechanism below the work comprising an oscillating support, a carrier lever mounted to rock on the support about an axis substantially at right angles to the axis of the support, loop engaging points on the carrier lever, and actuating connections for rocking 55 the carrier lever connected therewith at a point substantially in the axis of the support.
12. A sewing machine, having, in combination, an upper needle mechanism above 60 the work, and looper and loop spreader mechanism below the work comprising an oscillating looper carrier provided with looper points, a spreader carrier mounted to rock on the looper carrier and provided with loop spreader points, and actuating connections for the spreader carrier connected therewith at a point substantially in the axis of the looper carrier.
13. A sewing machine, having, in combination, an upper needle mechanism above the work, and looper and loop spreader mechanism below the work comprising two carriers mounted to oscillate in unison, looper and loop spreader points on the carriers, and mechanism for oscillating one of the carriers about an axis substantially parallel to the direction of travel of the points.
14. A sewing machine, having, in combination, an upper needle mechanism above the work, and looper and loop spreader mechanism below the work comprising an oscillating support, and a carrier mounted on the support to oscillate about an axis substantially at right angles to the axis of the support and provided with loop engaging points.
15. A sewing machine, having, in combination, a rotary upper needle mechanism, a turret below the work, looper and loop spreader carriers on the turret provided with looper and loop spreader points, mechanism for reciprocating the carriers in unison to introduce the points into and withdraw them from the needle loops, and mechanism for reciprocating one of the carriers 90 transversely twice for each reciprocation of the carriers in unison.
16. A sewing machine, having, in combination, a rotary upper needle mechanism, a turret below the work, looper and loop spreader carriers on the turret provided with looper and loop spreader points, rocking levers below the turret, and links connecting the levers and carriers.
17. A sewing machine, having, in combination, a rotary upper needle mechanism, a turret below the work, looper and loop spreader carriers on the turret provided with looper and loop spreader points, rocking levers below the turret, and adjustable links 110 connecting the levers and carriers.
18. A sewing machine, having, in combination, a rotary upper needle mechanism, a turret below the work, looper and loop spreader carriers on the turret provided with looper and loop spreader points, rocking levers below the turret, and tubular links connecting the levers and carriers and arranged one within the other.
19. A sewing machine, having, in combination, a rotary upper needle mechanism, a turret below the work, an oscillating looper carrier on the turret, loop spreaders mount-

ed on the carrier, two rocking levers below the turret, and links connected to operate the looper carrier and loop spreaders and having their lower ends connected with the 5 levers by ball joints.

20. A sewing machine, having, in combination, a rotary upper needle mechanism, a turret below the work, an oscillating looper carrier on the turret provided with looper 10 points, coöoperating loop spreaders on the carrier, a lever below the turret, a link having its upper end pivoted to the carrier and having its lower end connected with the lever by a ball joint, and means for operating 15 the loop spreaders.

21. A sewing machine, having, in combination, an oscillating carrier, a second carrier mounted to oscillate with and transversely of the first carrier, looper and loop 20 spreader points on the carriers, and mecha-

nism for oscillating the second carrier at double the frequency of the other carrier.

22. A sewing machine, having, in combination, an oscillating carrier having two arms in which two opposed loop entering 25 points may be secured, a second carrier mounted to rock transversely on the first carrier and having two arms in which two opposed loop entering points may be secured, and mechanism for oscillating the 30 first carrier and for oscillating the second carrier at double the frequency of the first carrier.

23. A sewing machine, having, in combination, an oscillating carrier, a second carrier 35 mounted to oscillate with and transversely of the first carrier, and sockets in the carriers for carrying two pairs of opposed loop entering points.

GEORGE S. HILL.
